UNITED STATES PATENT OFFICE

STEVE SCHNELL, OF ST. LOUIS, MISSOURI, ASSIGNOR TO WAGNER ELECTRIC CORPORATION, OF ST. LOUIS, MISSOURI, A CORPORATION OF DELAWARE

BRAKE BAND

Application filed February 26, 1932. Serial No. 595,260.

My invention relates to braking apparatus and more particularly to brake shoes, its principal object being to produce an improved brake shoe of the reinforced "band" type in which the distribution of pressure between the shoe and the drum is controlled by separating selected portions of the web from the lining carrying element. A secondary object is to increase the flexibility of the shoe.

Other objects of my invention will become apparent from the following description taken in connection with the accompanying drawing disclosing several embodiments thereof. Figure 1 is a side elevation of a brake disclosing the preferred form of my improved brake band; Figure 2 is a cross sectional view of the band on the line 2-2 of Figure 1; Figure 3 is a view illustrating one method of separating the web from the plane of a T section band; Figures 4 and 5 are cross sectional views of modified brake bands; Figure 6 is a side elevation of a brake shoe of the band type produced from a separate web and flange welded together (the drum being omitted); and Figure 7 is a cross sectional view on the line 7-7 of Figure 6.

Referring to Figures 1 to 3, the numeral 1 indicates the drum of the brake which is secured in the usual manner to the wheel of the vehicle and is enclosed on its open side by the backing plate or support 2 secured to some fixed part of the vehicle. The brake shoe 3 is shown as the reinforced band type and is mounted within the drum and adapted to have its free ends expanded into engagement therewith by suitable means, such as the hydraulic mechanism 4. The brake shoe 3 is shown as the T section form, although it may be of the channel type if desired, and comprises a drum engaging element or flange 6 and an integral web 5. The center of the web is shown as provided with an elongated opening 7 for the reception of an anchor pin 8 carried by the support 2.

When brake shoes of uniform cross section are applied to the drum, the pressure between the shoe and the drum is not uniform over the entire surface of contact. The difference in pressure is due to the "wrapping effect" of

the shoe and in band brakes the additional effect of the uneven bending movement of the band. In the type of brake illustrated in Figure 1 when an anchor is used at the center of the band the maximum pressure between the shoe and the drum will occur on the forward side of the anchor. To decrease this maximum pressure and do away with the resulting disadvantages such as uneven wear of the lining, "squealing", etc., I have conceived the idea of increasing the flexibility of the shoe over the portion having the excessive high pressure by separating the web at this point from the drum engaging element or flange.

In Figures 1 to 3, I have disclosed one method of increasing the flexibility of the shoe at the place desired by separating the web 5 from the flange 6. The band is first formed in the usual manner by shaping the desired length of T section steel to conform with the circumference of the drum. The portion of the flange that is joined by the web is then cut away over the part of the circumference of the band that is desired to be made more flexible. This cutting is best performed by the use of a milling cutter 9 of the proper diameter, as clearly shown in Figure 3. The cutter is allowed to cut completely through the flange 6 and also cut away a small portion of the web 5. The cut-away portion of the band allows the web and the flange to have relative movement when the band is expanded by the actuating mechanism 4 and the band, therefore, will not have the pressure on the drum that it would have if its flexibility had not been increased. The increasing of the flexibility of the band over the portion of maximum pressure also has the effect of distributing the maximum pressure.

Figures 4 and 5 illustrate two other methods of separating the web from the flange which I may employ to secure the same result attained by the method shown in Figure 1. In Figure 4 the web is separated from the flange by cutting away the web where it joins the flange by a straight cut through the web. In Figure 5, instead of cutting straight through the web by means of one
